UNITED STATES PATENT OFFICE.

MARIE JOSEPH CORNU, OF PARIS, FRANCE.

MERCURY-VAPOR LAMP.

1,400,346.

Specification of Letters Patent. Patented Dec. 13, 1921.

Application filed February 28, 1918. Serial No. 219,731.

To all whom it may concern:

Be it known that I, MARIE JOSEPH CORNU, a citizen of the French Republic, and residing in Paris, France, 26 Rue de Babylone, officer, have invented certain new and useful Improvements in and Relating to Mercury-Vapor Lamps, of which the following is a complete specification.

This invention relates to improvements in the mercury lamp, having in view more particularly a damper of the oscillations of the mercury, an arc-striking device and various constructional forms of current-supply arrangements.

15 The damper comprises a semi-capillary tube inserted in the path of the mercury between the illuminating tube and the compression tube connected to the anode, the said tube admitting of being traversed by a metallic conductor which effects the electrical connection between the two parts. The arc-striking device comprises a tube communicating with the highest point of the illuminating tube through the medium 20 of a capillary tube provided with small condensing chambers, a heating spiral traversing the arc-striking tube being connected in series with the lamp. The cathode of mercury may be replaced by a cathode of any 25 other metal, and the illuminating tube may be placed horizontally or vertically.

The accompanying drawing, illustrates by way of example various constructional form of the improved mercury lamp:—

30 Figure 1 is a longitudinal general view of the mercury lamp not in operation and shown partly in section.

Fig. 2 is a transverse view of Fig. 1.

Fig. 3 is a plan of Fig. 1.

40 Fig. 4 is a detail of the damping device.

Fig. 5 is a constructional form of the lamp, wherein the cathode of mercury is replaced by a cathode composed of another metal.

45 Fig. 6 is a similar constructional form, but with the illuminating tube placed vertically.

The damper of the oscillations of the mercury (Fig. 1 and Fig. 4) comprises a semi-capillary tube *a* which enters the anode chamber *b* and which constitutes an obstacle between the illuminating tube *c* and the compression tube *d* and through which the mercury can only pass very slowly.

In order to insure in a reliable manner 55 the electrical connection between these two parts, which communication might be interrupted if gaseous bubbles remained imprisoned in the capillary tube *a*, an auxiliary metallic wire *e* is arranged, the latter being 60 welded at the entrance of the capillary tube *a*, or placed within the said tube.

The arc of the lamp is struck in the following manner:—

When the lamp is not in operation the 65 arc-striking tube *f*, is filled with inert gas or vapor, such as neon, argon, nitrogen or the like. The inclosed tube *f* incloses a heating spiral *g* which is in relation at one end with the positive pole of the generator 70 and at the other end with the mercury of the anode.

This tube *f* is in communication, by means of a capillary tube *h*, with the highest point 75 of the illuminating tube *c*.

The cathode *i* is in communication, by means of the current-supply *j* with the negative pole of the generator.

The operation is as follows:—

When the current passes into the lamp 80 the temperature of the heating spiral *g* rises, the gas contained in the tube *f* expands, the level of the mercury which was at KK' when in a state of rest becomes lower in the illuminating tube *c* and rises 85 in the compression tube *d*. As soon as the mercury separates the arc is produced and extends in the direction of the anode *I* while the mercury continues to rise in the compression tube *d*.

The normal current being weaker than the arc-striking current, the temperature of the compression tube falls and the gas therein resumes its original place.

It will be observed that the capillary tube 90 *h* which unites the heating lamp *f* to the illuminating tube *c*, comprises two or more small condensation bulbs *m*, *m'*, *m''* the object of which is to maintain in the said tube, during operation a small quantity of mercury. This device prevents suction movements of the mercury in the capillary tube, and prevents the fall of drops of mercury into the illuminating tube during operation.

The arrangements indicated above being 100 maintained in a general way the mercury lamp may be modified by replacing the mercury cathode *i* (Figs. 1, 2 and 3) with a

cathode *n* (Figs. 5 and 6) formed of another metal such as iron, platinum, iridio-platinum, tungsten or others.

At the moment of striking, the arc is produced between this cathode *n* and the mercury meniscus of the anode.

Nothing is changed either in the arc striking or in the actual operation of the lamp.

The lamp described possesses the property of being able to strike its arc just as well by mere rocking as by the action of the expansion of the gas under the influence of the heating lamp.

The semi-capillary tube *a* may be placed at any other point on the path of the mercury between the illuminating tube *c* and the tube *d*.

What I claim is:

1. In a mercury vapor lamp, a stationary illuminating tube, a compression tube connected to the anode, a semi-capillary tube inserted in the path of the mercury between the said illuminating tube and the said compression tube, means assuring the electric connection between the two parts, and an arc-striking device.

2. In a mercury vapor lamp, a stationary illuminating tube, a compression tube connected to the anode, a semi-capillary tube inserted in the path of the mercury between the said illuminating tube and the said compression tube, a metallic conductor traversing the semi-capillary tube and connecting the two parts, and an arc-striking device.

3. In a mercury vapor lamp, an illuminating tube, a compression tube connected to the anode, a semi-capillary tube inserted in the path of the mercury between the said illuminating tube and the said compression tube, means assuring the electric connection between the two parts, an arc-striking tube, a capillary tube connecting the said arc striking tube to the illuminating tube, small

condensing chambers provided in the connecting tube, heating means provided in the arc-striking tube.

4. In a mercury vapor lamp, an illuminating tube, a compression tube connected to the anode, a semi-capillary tube inserted in the path of the mercury between the said illuminating tube and the said compression tube, means assuring the electric connection between the two parts, an arc-striking tube, a capillary tube connecting the said arc striking tube to the illuminating tube, small condensing chambers provided in the connecting tube, a heating spiral traversing the said arc-striking tube and connected in series with the lamp.

5. In a mercury vapor lamp, a stationary illuminating tube, a compression tube connected to the anode, a semi-capillary tube inserted in the path of the mercury between the said illuminating tube and the said compression tube, means assuring the electric connection between the two parts, an arc-striking tube, a capillary tube connecting the arc-striking tube with the illuminating tube, and a metallic cathode other than mercury.

6. In a mercury vapor lamp, an illuminating tube, a compression tube, an arc-striking tube having a heating spiral therein, connections between the said tubes, a semi-capillary tube in the connection between the illuminating and the compression tubes, a metallic conductor traversing the semi-capillary tube, and a capillary tube connecting the arc-striking tube with the illuminating tube.

In testimony whereof I have hereunto set my hand at Paris (France), this 5th day of February, 1918.

MARIE JOSEPH CORNU.

In the presence of a witness:

CHAS. P. FRESSLY.
